UNITED STATES PATENT OFFICE

AXEL M. PETERSON, OF DENVER, COLORADO

ANTICREEPING RAIL AND COOPERATING TIE PLATE FOR RAILWAYS

Application filed January 20, 1930. Serial No. 422,025.

My invention relates to an anticreeper rail and cooperating tie plate for railways and is designed as an improvement over Patent No. 1,671,377 for an anticreeper rail and tie plate construction for railways, which was granted to me on May 29, 1928.

The main object of the present invention is to provide an improved tie plate and cooperating rail which connects with the said tie plate in such manner as to prevent creeping of the said rail in either direction beyond the natural expansion and contraction due to temperature.

Further, to provide a tie plate having a series of elongated teeth and a rail having corresponding teeth formed in its base flange but flush with the surface thereof, which interlock with the teeth on the said plate, the rail being spiked to the tie in the usual manner, the spikes passing through the said plate, whereby creeping of the rail in either direction is prevented; the plate being also secured to the cross tie by lag screws whereby upward movement of the plate, due to vibratory action and the consequent loosening of the spikes is prevented.

Further, to provide a plate of this character having a boss of greater height than the teeth on said plate to form a rest for the rail to prevent the same from striking the teeth when the said rail is slid into position against the abutment rib.

These and other objects which will be hereinafter referred to, are accomplished by the construction embodied in the accompanying drawings in which,—

Fig. 1 is a vertical transverse sectional view through a rail and tie plate constructed in accordance with my invention, the rail and plate being spiked to a cross tie.

Fig. 2 is a longitudinal sectional view through the plate and the base portion of the rail.

Fig. 3 is a perspective view of the improved tie plate looking at the upper side thereof.

Fig. 4 is a similar view looking at the under side thereof, and

Fig. 5 is a bottom plan view of a portion of a rail embodying the improved construction.

In the present practice of track construction for railways, the rails rest either directly upon the ties or upon smooth metal plates which are placed upon the ties and are secured to the ties by spikes which pass through holes in the plates, the heads of the spikes engaging the rail flange. This method, however, permits creeping of the rails under the rotary action of the car wheels, particularly on heavy grades or under the frictional engagement of the wheels with the rails when the brakes have been applied, whereby the fish plates connecting the adjoining ends of the rails are frequently broken, thus permitting the connected rails to be drawn apart or disconnected. The construction embodied in the present application, however, positively prevents creeping of the rails by providing a locking connection between the rails and tie plates, as will now be particularly set forth.

Referring to the accompanying drawings, the letter A designates the improved tie plate which is rectangular in form and about ten inches long by about seven inches wide. The upper side of this plate, near one of its short edges, is formed with a vertically disposed transverse rib 1, which extends the full width of the plate and is about three eighths of an inch high. The inner face of this rib forms an abutment shoulder for one edge of the rail flange and from this shoulder the upper face of the plate has a slight downward inclination to a point X and from the point X a slightly greater downward inclination to the adjacent short edge of the plate, as clearly shown in the drawings. The outer side of the rib 1 inclines down to the face of the plate from which point the face of the plate has a slight downward inclination to the adjacent short edge thereof. A plurality of longitudinally disposed teeth or projections 2 are formed on the upper face of the plate and midway of its length, these teeth being relatively long and of slightly less width than the space between them. The long edges of these teeth are slightly rounded and their ends are beveled at an angle to the face of the plate. Transverse grooves or channels 3 are formed in the

face of the plate adjoining the ends of the teeth 2, and square spike receiving holes 4 and 5 are formed through the plate, the holes 4 being cut through the abutment rib 1 and so that the inner faces of the said holes coincide with the line of the inner face of the rib as shown most clearly in Fig. 3. The channels 3 receive and carry off any dirt or grit that may collect between the teeth of the plate and rail. The inner edges of the holes 5 coincide with the line or point X on the plate, the distance between this point and the inner edge of the rib 1 corresponding to the width of the rail flange and between the holes 5, a lug or boss 6 is formed on the plate, which is of slightly greater height than the height of the teeth 2, the purpose of this boss being later mentioned. The under side of the plate A is on a horizontal plane from the inner short edge of the plate to a line Y which coincides with the outer edges of the holes 4 and from the line Y the face of the plate inclines slightly upward to its adjacent edge. Longitudinal ribs 7 extend from the inner edges of the spike holes 4 to the inner edges of the spike holes 5, the sides of these ribs being curved to a blunt edge and their ends being beveled. As these ribs are parallel with the grain of the ties, they are embedded in the tie to a slight depth when the rail is spiked, thus assisting in holding the plate against movement on the tie. The plate is further provided with holes 8 adjacent its short edges and centrally of its width, and these holes extend through bosses 9 on the under sides of the plate, the faces of which are on a corresponding level with the edges of the ribs 7. Lag screws 10 are passed loosely through these holes and screwed into the ties after the rail has been spiked and these screws prevent upward movement of the plate due to vibratory action, which otherwise, would tend to loosen the spikes. As the ribs 7 and the bosses 9 are the only parts of the plate in direct contact with the tie, they become embedded in the tie under the weight imposed upon the plate and the plate is thus more evenly seated upon the tie than would be the case if the entire face of the plate rested on the tie.

In connection with the improved tie plate above described, I employ a rail 11 which in all respects is identical with rails in present use with the exception that the bottom face 55 of its base flange is formed centrally of its width with transverse elongated teeth 12. These teeth are rolled into the rail in the process of its manufacture and extend throughout the length of the rail. The faces of these 60 teeth are flush with the bottom face of the rail flange and parallel longitudinal channels 13 are rolled into a rail flange in the same operation that forms the teeth and these channels define the length of the teeth and coincide 65 with the channels 3 in the tie plate. The ends

of the rails are cut by gauge so that when the ends of two rails join on a tie plate, there will be no break in the continuity of the rail teeth 12 and the two rails will join and fit down on the teeth 2 of the tie plate, the same as a single rail. The inclined upper faces of the tie plates will cause the parallel rails to incline slightly towards each other, as will be seen by reference to Fig. 1.

In practice, the plates A are placed upon the ties and the rail is then laid upon the plates but so as to rest upon the lugs or bosses 6, which are slightly higher than the teeth 2 on the plates, so that when the rails are slid over to engage the abutment ribs 1, the edge of the rail will not strike against the edges of the teeth 2 of the plates but will pass over them until the said rail slides off from the lug, thus permitting its teeth to interlock with the teeth of the plates and breaking or marring the teeth on the plates is thus prevented. Spikes 14 of the usual type are then driven through the holes 4 and 5 in the plates and into the tie, the heads of the spikes engaging the rail flange in the usual manner. The lag screws 10 are then passed through the holes 8 in the plate and are screwed into the tie, their heads bearing upon the plates, thus securely holding the plates against upward movement due to rail vibration. Thus the plates are immovably secured to the ties and the rails are immovably secured to the plates by reason of the interlocking engagement of the teeth 2 on the plates and the teeth 12 on the rail and creeping of the rails on the plates is thereby prevented, resulting as frequently happens in the breaking of the fish plates which connect the rails with the possible serious consequences due to such an accident, together with the time and expense necessary in repairing such damage.

Having described my invention, what I claim as new and desire to secure by Letters Patent, is:

1. In mechanism of the character described, a railway tie plate provided on its top face with an abutment rib from which point the face has a slight downward inclination, a row of elongated teeth on said face at right angles to said rib, and spike receiving holes, two of which extend through said abutment rib; parallel ribs on the under side of the plate which extend at right angles to the said abutment rib; bosses on the underside of the plate having holes extending through them and through the plate for the reception of retaining screws; in combination with a rail having teeth on the under side of its base flange and parallel longitudinal grooves which define the length of said teeth, said teeth being interlocked with the teeth on the plate, thereby to prevent creeping of the rail upon the plate, said rail base resting against said abutment rib.

2. A railway tie plate having an abutment

rib near one end from which point the plate diminishes in thickness toward the opposite end, a central row of projecting teeth at right angles to said rib; spike receiving holes, one 5 pair of said holes being cut through said rib, a boss being formed between the other two holes which is of greater height than said teeth; a pair of ribs on the under side of the plate which extend at right angles to the said 10 abutment rib, and bosses on the under sides of the plate near the ends thereof, having holes therethrough and through the plate for the reception of retaining screws.

In testimony whereof, I affix my signature.
